WIREDRAWING MACHINE

Filed Nov. 12, 1931

UNITED STATES PATENT OFFICE

VALENTIN WEIL AND HERMANN GUTMANN, OF FRANKFORT-ON-THE-MAIN, GERMANY

WIREDRAWING MACHINE

Application filed November 12, 1931, Serial No. 574,658, and in Germany July 19, 1930.

This invention relates to improvements in wire drawing machines generally, and more particularly to a multi-wire drawing type thereof, wherein a plurality of drawing sheaves are grouped about a common center, with the object that a single drawing drum is constituted thereby, with its circumference divided into a plurality of bearing surfaces to reduce the drawing angle of the wires passing about the same.

Another object of the invention is to provide a drum of this character, wherein its surface is either provided with longitudinal ribs or grooves, or it is composed of a plurality of cylindrical, polygonal, or conical rods or tubes, which are independently demountable for replacement purposes and similarly adjustable for renewing the bearing surfaces, as required.

A further object of the invention resides in constructing the machine in a manner that its operating parts may be subjected to a cooling medium, in order to reduce destructive friction heating effects to a minimum and thereby prolong the life of such parts.

With the foregoing and other equally important objects and advantages in view, the invention resides in the certain new and useful combination, construction and arrangement of parts as will be hereinafter more fully described, set forth in the appended claims, and illustrated in the accompanying drawing in which:—

Figure 1 is a vertical transverse section, Figure 2 is a vertical longitudinal section, Figure 3 is a cross-sectional view of a modified form of drawing sheave,

Figure 4 is a similar view of a modified form of drawing sheave,

Figure 5 is a side elevation, partly in section, of one of the drawing sheaves as in Figure 1, but modified to show alternately arranged and reversely tapered bearing surfaces therefor,

Figure 6 is a side elevation, partly in section, of a stepped form of drawing sheave,

Figure 7 is a diagrammatic view of the improved machine, and,

Figure 8 is a view similar to that of Fig-

ure 7, but of an old type of wire drawing machine, by way of comparison.

Referring to the drawing, wherein like characters of reference designate corresponding parts in the several views thereof, and more particularly to Figures 1, 2 and 7, the embodiment of the invention, as is exemplified therein, has each drawing sheave made up of a plurality of bearing surfaces having the form of cylindrical rods or tubes 1 which are arranged in circular series and centered about a shaft 2 and in a manner as to be readily removed, replaced and adjusted. The rod or tube members 1 are for this purpose held at their ends on pins 11 which are secured to flanges 9 and which may taper toward their free ends. The members 1 can be removed by a loosening of the nuts 10, which hold the flanges 9 in position, and by removal of a plate 14 whereby the different sheaves are supported. The members 1 can also, after a loosening of the nuts 10, each be adjusted about their axes for turning movements to present a new bearing surface to the wires passed about the drum.

By this arrangement, the entire circumference of the members 1 can be utilized. Instead of being cylindrical, however, the members 1 may taper slightly either towards the middle or towards the ends, and inwardly tapering members may alternate with outwardly tapering ones. The entire drum structure can easily be dismounted after the removal of a bearing bracket 16 and a supporting plate 17.

The employment of conical members 1 has the advantage that the wires to be drawn will be caused to travel to and fro in a horizontal direction as well as in the vertical direction, determined by the succession of isolated bearing surfaces, and the wire will thus describe substantially the surface of a cone, the apex of which is situated in the die. Thus the die will be subjected to a uniform pull. The same effect may be obtained if the die holder is subjected to a reciprocating movement in its own plane in a horizontal direction.

The machine is particularly adapted for the drawing of fine wire, and two or more

sheaves are employed which may be geared together and to a driving element by means of gears 5 and 6. Figure 1 shows an arrangement with five sheaves arranged in 5 circular series about a common center, and Figure 7 an arrangement with three of the same. In either instance, a delivery reel 8 and a take-up reel 7 is provided, with dies 3 arranged between two of the upper 10 sheaves.

In any case, the sum of all the bearing surfaces is smaller than the continuous bearing surface of a single massive drawing drum, so that the detrimental circumferential friction will be reduced to a minimum. 15 By way of demonstrating the advantage of the present novel arrangement, it is compared in Figures 7 and 8 with an old arrangement, the Greek letters indicating the 20 different angles.

When tubes are employed as bearing surfaces, they may conveniently be utilized as conduits for the circulation of a cooling medium therethrough. The machine may also 25 have the protection of a hood 15 which covers the dies 3, as well as the sheave-drum structure, and allows all to be uniformly swept with the cooling medium admitted through an inlet 18.

30 The hood 15 may be provided with glass-covered inspection apertures, as will be well understood.

This multi-surfaced bearing for the wires to be drawn may be obtained by providing 35 continuous drum surfaces with grooves 19, as shown in Figure 3, or with ribs 20, as shown in Figure 4.

Practical tests have shown that the increased length of the wire produced by the 40 reduction of wire diameter, will be satisfactorily taken up by the machine. This is the case even when very hard material is used, for instance chrome-nickel, and the like, and when the diameter is reduced in 45 the first die up to twenty per cent. Also, and if desired, a drawing sheave may be made to a stepped construction, as is shown in Figure 6.

Without further description, it is thought 50 that the features and advantages of the invention will be readily apparent to those skilled in the art, and it will of course be understood that various changes in form, proportion, and minor details of construction 55 may be resorted to, without departing from the spirit of the invention, or its scope as claimed.

We claim:

1. In a wire drawing machine, a driving 60 shaft, a plurality of drawing sheaves arranged in circular series about the axis of the shaft, and means driven by the shaft for imparting simultaneous rotary motion to said sheaves, said sheaves each being formed 65 to provide a plurality of circularly spaced

longitudinally extending bearing surfaces, whereby the wire is drawn by each of the sheaves by contact with a lesser number of the bearing surfaces than the total number on each sheave and the wire travels in a straight line from one bearing surface to the next following. 70

2. The machine as set forth in claim 1, wherein the said bearing surfaces of each sheave are angularly adjustable to cause a uniform distribution of wear thereon. 75

3. The machine as set forth in claim 1, wherein the said bearing surfaces of each sheave are fixed and arranged to be independently renewed when worn and to be similarly adjusted to cause a substantially uniform distribution of wear thereover. 80

4. The machine as set forth in claim 1, wherein the said bearing surfaces are in the form of a plurality of spaced cylindrical members arranged in circular series about the axis of each sheave. 85

5. The machine as set forth in claim 1, wherein the said bearing surfaces are in the form of spaced tubular members arranged in circular series about the axis of each sheave. 90

6. The machine as set forth in claim 1, wherein the said bearing surfaces are in the form of spaced tapered tubular members arranged in circular series about the axis of each sheave and in alternately reversed end for end position one relatively to the other. 95

7. The machine as set forth in claim 1, wherein drawing dies are arranged for co-operation with the drum and both the dies and drum are enclosed within a hood through which a cooling medium is to be circulated. 100

8. The machine as set forth in claim 1, wherein the said bearing surfaces are in the form of hollow members and the drum structure is enclosed within a hood whereby a cooling medium may be circulated therethrough. 105

In testimony whereof we affix our signatures.

VALENTIN WEIL.
HERMANN GUTMANN.
